PORTABLE INSULATED ICE CHEST

Marten Gottsegen, Chicago, Ill., assignor to Gotham Industries, Inc., Chicago, Ill., a corporation of New York

Filed Aug. 30, 1963, Ser. No. 76,407

Term of patent 14 years

(Cl. D58—17)

FIG. 1 is a side elevational view of a portable insulated ice chest embodying my new design;

FIG. 2 is an end elevational view thereof;

FIG. 3 is a top plan view thereof; and

FIG. 4 is a bottom plan view thereof.

The side and end of the ice chest not shown are substantially the same as the side and end shown.

I claim:

The ornamental design for a portable insulated ice chest, substantially as shown and described.
